FLASHLIGHT

Sidney Schwartz, New York, N.Y., assignor to Bantam-Lite, Inc., New York, N.Y., a corporation of New York

Filed Aug. 6, 1963, Ser. No. 76,127

Term of patent 14 years

(Cl. D48—24)

FIG. 1 is a front elevational view of a flashlight showing my new design.

FIG. 2 is a top plan view.

FIG. 3 is a rear elevational view, and

FIGS. 4 and 5 are left and right side elevational views, respectively, as seen in FIG. 1.

I claim:

The ornamental design for a flashlight, as shown.
